UNITED STATES PATENT OFFICE

JASPER BLACKBURN, OF WEBSTER GROVES, MISSOURI

GUY STRAND GUARD AND LOCK

Application filed March 3, 1932. Serial No. 596,459.

This invention relates to guards for guy strands of any kind or nature, but particular reference is here had to guy wires or cables as commonly used for supporting telephone poles and the like. These wires are usually of relatively small diameter and constitute therefore, if left unguarded, a positive danger to pedestrians who in their haste might overlook the small wires and walk into them.

The principal object of the invention is to provide a relatively simple, strong and practical guard which may be quickly and firmly mounted in place upon such guy wire and which will be easily seen and serve to notify and warn pedestrians of the presence of the guy wire.

Another object is to provide a guard of the kind described, comprising in combination with an elongated member of the form of a parted tube or sleeve adapted for seating over the guy wire, spaced locking members mounted within the sleeve, the said locking members being each provided with a set of gravity dogs or lugs so arranged that while they will readily permit transverse insertion of the guy wire to a central position within the assembly, they will then, through the action of gravity, fall into a locking position relative to the said guy wire, thereby preventing its withdrawal.

Another object is to provide in a guard of the kind described, various forms of guy wire locks operable through gravity, any one of which when seated within a tubular member will serve to lockingly engage and hold a guy wire transversely inserted therein.

Another object is to provide a form of guy wire lock including a block suitably formed for mounting within a tubular guard member, the said block being apertured or recessed centrally and having an opening out through one margin, and there being gravity dogs or lugs so formed and mounted upon the block as to readily admit the transverse insertion of a guy wire, while preventing the removal thereof after such insertion.

With these and such other objects and advantages in view, as may be disclosed in the following specification, attention is directed to the accompanying drawings exemplifying

certain preferred embodiments of my invention and wherein:

Figure 1 is an elevation showing an assembly of anchor rod, guy wire and tubular guard, the guy wire or cable locks which are the principal subject matter of this invention, being indicated in dotted lines, as mounted in spaced relation within the guard. 55

Figure 2 is a view similar to Figure 1, showing a somewhat different arrangement of the elements and including a caplock at 60 the lower end of the assembly.

Figure 3 is a bottom plan view of the preferred form of tubular wire guard, showing the longitudinal opening at this side, 65 the said cable or wire locks being here also indicated in dotted lines.

Figure 4 is an elevation on a scale enlarged to approximate life size, of one form of guy wire or cable lock, the subject matter 70 of my invention, the tubular guard and guy wire being shown in section, with the guy wire in locked position.

Figure 5 is a medial longitudinal section through the form of guy wire lock shown 75 in Figure 4, the guard and wire being omitted.

Figure 6 is a longitudinal section on the line 6—6 of the assembly shown in Figure 4, the guy wire however being shown in full 80 lines.

Figure 7 is a view similar to that of Figure 4, there being incorporated in the assembly a conventional form of stirrup for the lock screw to bear upon. 85

Figure 8 is a section on the line 8—8 of Figure 7.

Figure 9 is a fragmentary, longitudinal sectional view through an assembly of guy wire guard, and a special form of lock designed to act also as a cap at the lower end of such assembly, the said lock being here shown provided with two sets of gravity lugs of different lengths, the anchor rod itself being shown in full lines. 95

Figure 10 is a section on the line 10—10 of Figure 9.

Figure 11 is an inner end view of the form of cap lock shown in Figure 10.

Figure 12 is a longitudinal section through 100

another form of guy wire lock, the gravity operated wire engaging pins, lugs or fingers being shown in full lines as extended beneath the guy wire, the latter being shown in section.

Figure 13 is a view similar to that of Figure 12, the wire engaging lugs or pins being shown retracted in their sockets and the guy wire being omitted.

10 Figure 14 is an end view of still another form of gravity operated cable or guy wire lock, including a sectional view of the wire as held in locked position.

15 Figure 15 is a view similar to that of Figure 14, showing the guy wire as in process of entering the lock, whereby the wire engaging fingers are spread asunder.

Figure 16 is an edge view of the assembly of Figure 14.

20 Figure 17 is a detail view showing the addition of a torsional spring in the pivotal mounting of the gravity lugs or fingers as means assisting gravity or in lieu of gravity, for operating the said lugs.

25 In combination with a suitable tubular or sleeve-like guy wire guard 1, formed usually by merely rolling up an elongated strip of sheet metal into the form of a split or parted tube so as to provide the longitudinally extended opening or mouth 2, my invention comprises various forms of gravity locks A, B, C and D for mounting in spaced relation along within the said guard and which are adapted and operable through gravity to engage and 30 lockingly retain the guy wire or strand 7 or the anchor rod 8, as the same are transversely inserted into the guard 1 through its said mouth 2. As shown in Figures 4, 5, 6, 7, the lock here designated by the letter A, in one preferred form includes a flat, circular or cylindrical lock block 9 having formed in its intended lower or skirt portion, a transverse guy wire opening or cable-way 10 extended through both faces of the block, and also the 35 right angularly extended lug sockets or recesses 11, the said lower part of the block being thus quartered into four branches or webs 12 depending from the upper shoulder 13. The shoulder 13 is pierced with a screw socket 14, the same being tapped down through into the cable-way 10, as shown at 40 15, thereby providing a threaded bore for the set or lock screw 16 as well as the said socket for the screw head.

50 A pair of elongated, rectangular lock lugs 17 are pivotally mounted upon pins 18, the ends of the pins being rigidly anchored or set in the opposed adjacent branches or webs 12 at each side of the cable-way 10, the said pins passing loosely through the said lugs. Or, 55 the arrangement might, of course, be reversed, the essential being that the lugs swing freely from side to side within their sockets. The described parts are so dimen-

sioned and arranged that the lock lugs 17 may swing up into their sockets substantially clear of the cable-way 10, as shown in Figure 5, or under the action of gravity may swing down and out transversely across the cable-way, as shown in Figure 4. A number of these lock blocks thus prepared and arranged may be mounted in spaced relation along and within the guard 1, as shown at A, B, C, D in Figures 1, 2 and 3, these figures being 70 illustrative of the application and spaced 75 mountings of any form of guy wire lock as conventionally practised. In order to anchor the locks within the guard so that they will not slide or slip longitudinally out of place, the margins 19 of the guard at the mouth 2 may be bent or turned sharply inwardly at 80 an angle to form flanges 20 and seated in recesses 21 formed at the inner margins of the webs 12. The flanges 20 may then be cut through transversely at each side of the block 9, that is to say, at the outer sides of the depending webs 12, and bent still further back across the outer faces of the said webs, as shown at 22, thereby locking the 85 blocks against movement.

90 In the use of the invention in the form described, the guard so equipped with a number of the prepared blocks 9, is passed down over the lower portion of the guy wire 7 and the upper portion of the anchor rod 8, as illustrated in Figure 1, the said wire entering through the mouth 2 and passing up into the cable-ways 10 of each block. In this operation, the strand of wire will strike upon the inwardly and downwardly turned ends of the lock lugs 17, pushing them up and passing between them to the upper ends of the lugs. These lugs thus being released, fall back 95 down again below the guy wire or strand and prevent the retraction of the wire through the passage 10. The several screws 16 are then turned down upon the upper side of the guy wire or cable, thereby securely locking same in place and anchoring the guard itself against any longitudinal slippage relative to the guy wire. The outer lower corners 23 of the lugs 17 may be rounded off so as not to interfere with the adjacent guard wall. On 100 the other hand, the opposite corners 24 are preferably left square so as to abut upon the said guard wall when turned down and out, whereby they are maintained in the proper set position for receiving and engaging the 105 guy wire.

110 If desired, a bearing stirrup 25 may be provided at the lower inner end of each screw 16, the same resting upon the cable or guy wire 7 and the screw in turn pressing upon the 115 stirrup, thereby lessening the danger of damage to the wire. The stirrup 25 includes upwardly turned fingers 26 having ends 27 turned inwardly and slidably seated within slots or grooves 28 formed in the sides of the 120

shoulder 13, whereby the stirrup is movably mounted in position.

As shown in Figures 9, 10 and 11, in the form of lock designated by the letter B, double sets of lugs 17 and 17b are mounted upon the pins 18b. The lugs 17b are relatively longer than the lugs 17, whereby guy wires or anchor rods of various diameters may be engaged and locked. As will appear from 10 an inspection of Figure 10, if the wire 7 or rod 8 is of relatively large diameter, then as it is passed up through the cable-way 10, the set of shorter lugs 17 will first fall down under the wire or rod and serve the intended 15 purpose of locking the element in place. However, if the wire or rod be of relatively small diameter, it will pass on up between the set of longer lugs 17b, which will then fall out and down and serve to hold the wire or 20 rod in place against retraction. It is also evident that additional sets of lugs (not shown) may be provided, and of such length as may be desired. The Figures 9, 10 and 11 also illustrate a special form of cap-block 25 designed for mounting at the lower end of a guard, or over the lower end of a guard and the attached upper end of an anchor rod, as shown in Figure 2. This cap-block 9b is essentially similar to the others, but is of 30 larger diameter so as to provide marginal room for cutting or forming an annular groove 29 within which the lower end of the guard may be seated, as shown at 30 in Figure 9, whereby means are provided for preventing the lateral spreading of the walls of 35 the guard.

In Figures 12 and 13, illustrating the form of lock referred to as C, the block 9c is formed with downwardly and inwardly directed lug 40 sockets 11c, reduced at the lower ends so as to form shoulders 31, as shown. Lugs or fingers 17c are slidably mounted within these sockets and have heads 32 which impinge upon the shoulders 31 to limit their downward movement. These lugs through gravity normally fall to their lower and outwardly extended position as shown in Figure 12. The act of pressing the guard down in the process of seating the guard upon the guy 45 wire, causes the wire to force the lugs 17c slidably up into the sockets 11c, as shown in Figure 13. After the wire has passed the lower ends of the lugs, however, the said lugs will fall again to the position of Figure 12, 50 below the said guy wire, thereby locking same against retraction.

In Figures 14, 15 and 16, illustrating the form of lock designated as D, hooks 17d are pivotally mounted by pins 18d upon the upper side faces of the block 9d, and these hooks are directed inwardly towards each other and are so weighted at 33 as to normally, through gravity, fall down across the cable-way 10d at each side of the block. The hooks 55 are so formed and curved inwardly at their

lower margins however, that when in their said normal position under the influence of gravity and before the insertion of the guy wire, their said lower margins will present an inverted V-shaped formation towards the transverse insertion of the guy wire, as shown at 34. By virtue of this arrangement, the guy wire, as it is pressed up into this V-shaped formation, will act to spread asunder the hooks 17d, as shown in Figure 15. After 60 the wire is passed fully up into the cable-way 10d, however, the hooks will fall back to normal position and will then lie under the wire, and prevent its retraction, in manner similar to the other arrangements shown.

If desired, various forms of springs may be mounted in association with the several forms of lock lugs, fingers and hooks above referred to, for the purpose of assisting gravity or in lieu of gravity, for operating said elements. As illustrating this feature, there is shown at 35 in Figure 17, a torsional spring seated in the pivotal mounting of a lug 17. Likewise, springs can easily be adapted for use with the other forms shown.

It will be understood, of course, that any conventional structural features, as commonly found in such devices, may be readily incorporated and used in connection with the several embodiments of my invention as here shown, or any modification thereof; as for instance, the lock screws 16 and the bearing stirrups 25 as shown in several of the figures. And while I have herein set forth and described certain preferred embodiments and forms of my invention, together with certain structural details, I do not hold myself to be limited to these specific forms or details of structure, but may vary the same as desired, not departing from the spirit of the invention, as defined in the appended claims.

I claim:

1. A gravity control lock for mounting a tubular form of guard upon a guy strand, the guard having a longitudinal opening along one side, the said lock comprising a block seated within the guard and having a cable-way opening out through one margin in alignment with the guard opening, and locking members movably supported upon the block, the latter being formed to accommodate the same, the said locking members being normally movable by gravity athwart the said cable-way, and being formed at their lower margins so as to open apart under the pressure of the entering guy strand, and at their upper margins so as to lockingly hold the entered guy strand against retraction.

2. A lock for fastening a tubular guard upon a guy strand or the like, the said guard having a longitudinal opening along one side whereby it is set over the strand, the said block comprising a block seated within the guard and having an opening aligned with the opening of the guard and through which

the strand is passed, and locking elements upon the block formed and arranged to spread asunder under the transverse movement of the strand into the opening of the block, and to fall back again by gravity beneath the strand after the latter is moved fully into place.

3. A lock for mounting a tubular guard upon a guy strand or the like, the said guard having a longitudinally extended opening through and along one side, the said lock comprising a block seated within the guard and having an opening aligned with the opening of the guard, and gravity controlled locking elements on the block so formed and mounted as to open under the pressure of the guy strand to admit the latter transversely into the said opening of the block, and to fall back under the strand for lockingly holding the same in place.

20 4. A gravity controlled lock for mounting a tubular guard upon a guy strand, the said guard having a longitudinal opening along one side, the said lock comprising a block seated within the guard and having an opening therethrough aligned and communicating with the guard opening, and locking members upon the block adapted through gravity to close towards one another over the said block opening, the said members being so formed at their under sides as to spread apart under the pressure of the strand for admitting same within the block opening to a position above the said locking members.

5. A gravity controlled lock for mounting 35 a tubular form of guard upon a guy strand, a guard having a longitudinal opening along one side, the said lock comprising a block seated within the guard and having a cable-way formed therethrough registering with 40 the guard opening, and gravity locking members supported upon the block, the latter being formed to accommodate the same, the said gravity locking members being so formed and mounted as to move towards one another by gravity into co-operative strand locking 45 positions over the said cable-way, and being so shaped at their lower margins as to be spread apart under the pressure of the entering guy strand for admitting the same to 50 a position at the upper side of the said locking members, the latter being so formed at their upper sides as to prevent the retraction of the entered strand.

6. A gravity controlled lock for mounting 55 a tubular guard upon a guy strand, the guard having a longitudinally extended slot-like opening through its proposed lower side, the said lock comprising a block seated within the guard and having a cable-way opening 60 out through its proposed lower margin in alignment with the guard opening, the said block having lug sockets formed laterally of its cable-way, and elongated gravity lugs pivotally mounted at their lower ends within 65 in said sockets and arranged to fall by grav-

ity centrally athwart the said cable-way to an upwardly and inwardly inclined position.

7. A gravity controlled lock for mounting 70 a tubular guard upon a guy strand, the guard having a longitudinally extended slot-like opening through its proposed lower side, the said lock comprising a block seated within the guard and having a cable-way opening out through its proposed lower margin in alignment with the guard opening, the 75 said block having lug sockets formed laterally of its cable-way, and a plurality of elongated gravity lugs pivotally mounted at one end within the lower portions of the lug sockets and arranged to fall by gravity centrally 80 athwart the said cable-way to an upwardly and inwardly inclined position.

8. A gravity controlled lock for mounting 85 a tubular guard upon a guy strand, the guard having a longitudinally extended opening through its proposed lower side, the said lock comprising a block seated within the guard and having a cable-way opening out through its proposed lower side in alignment with the guard opening, the said block being recessed laterally of the said cable-way to form lug sockets, and a plurality of elongated gravity lugs of unequal lengths 90 vertically and pivotally mounted at one end within the lower portions of the lug sockets, the same being arranged to fall by gravity at their upper ends into the formation of an inverted V centrally athwart the said cable-way.

9. A gravity controlled lock for mounting 100 a tubular guard upon a guy strand, the guard having a longitudinally extended opening through its proposed lower side, the said lock comprising a block seated within the guard and having a cable-way opening out through its proposed lower margin in alignment with the guard opening, the said block being formed with downwardly and inwardly directed lug sockets arranged laterally of the said cable-way, and lugs slidably mounted within the said sockets and adapted normally to slidably fall by gravity to a position wherein their lower ends will project out centrally athwart the said cable opening, in a V-shaped formation.

10. A gravity controlled lock for mounting 105 a tubular guard upon a guy strand, the guard having a longitudinally extended opening through its proposed lower side, the said lock comprising a block seated within the guard and having a cable-way opening out through its proposed lower margin in alignment with the guard opening, and gravity hooks pivotally mounted upon the upper side faces of the block, the said hooks being turned towards each other and formed and arranged to normally through gravity fall down athwart the cable-way at each side of the block, the hooks being so formed and curved inwardly at their lower margins that 110

when in their said normal positions under the influence of gravity their said lower margins will present an inverted V-shaped formation towards the transverse insertion 5 of the guy wire.

11. In combination, a tubular guy strand guard having a longitudinally extended opening through one side, the margins of the guard at the opening being turned inwardly, 10 and a guy strand supporting block seated within the said guard, the said inturned margins of the guard being pinched athwart the faces of the block at each side thereof, to lock the same against longitudinal movement 15 within the guard.

12. In combination, a tubular guy strand guard having a longitudinally extended opening through one side, and a guy strand supporting block seated upon an end of the 20 guard, the margin of the block being grooved to engage the said end, whereby the guard is prevented from spreading asunder at its said opening.

13. A gravity control lock for mounting a 25 guard upon a guy strand, the said lock comprising a supporting element mounted upon the guard and having a cable-way opening out through one margin and locking members movably supported upon the element and 30 adapted by gravity to lockingly engage the guy strand as it passes transversely into the said cable-way.

14. A gravity control lock for mounting a 35 guard upon a guy strand, the said lock comprising a supporting element mounted upon the guard and having a cable-way opening out through one margin and locking members movably supported upon the element and adapted by gravity to lockingly engage 40 the guy strand as it passes transversely into the said cable-way, and means such as springs for assisting the action of gravity in the operation of the said locking members.

15. A gravity control lock for mounting a 45 guard upon a guy strand, the said lock comprising a supporting element mounted upon the guard and having a cable-way opening out therethrough, locking members movably supported upon the element and formed and 50 arranged to lockingly engage the guy strand under the action of gravity as the strand is passed transversely into the said cable-way, and additional co-operative locking means arranged oppositely to the said 55 locking members.

16. A gravity control lock for mounting a 60 guard upon a guy strand, the said lock comprising a supporting element mounted upon the guard and having a cable-way opening out therethrough, and a plurality of elongated gravity lugs pivotally mounted at one end upon the supporting element, the lugs being so formed, arranged and mounted as to admit the transverse insertion of the guy 65 strand into the cable-way past and between

the lugs, and thereafter to prevent the retraction of the guy strand reversely out through the cable-way.

17. A gravity control lock for mounting a 70 guard upon a guy strand, the said lock comprising a supporting element mounted upon the guard and having a cable-way opening out therethrough, and lugs slidably mounted upon the supporting element and adapted normally to slidably fall by gravity to a position wherein their lower ends will project out athwart the said cable-way.

18. A gravity control lock for mounting a 75 guard upon a guy strand, the said lock comprising a supporting element mounted upon the guard and having a cable-way opening out therethrough, and gravity hooks pivotally mounted upon the supporting element, the said hooks being turned towards each other and formed and arranged to normally 80 through gravity fall athwart the cable-way of the said supporting element, the hooks being so formed and curved inwardly at their lower margins that when in their said normal positions under the influence of gravity, 85 their said lower margins will present an inverted V-shaped formation towards the transverse insertion of the guy strand for admitting the guy strand into the cable-way.

In testimony whereof, I affix my signature. 90
JASPER BLACKBURN.
